A. H. NEILSON

SAFETY HOOK

Filed Oct. 1, 1924

UNITED STATES PATENT OFFICE.

ALBERT HOWARD NEILSON, OF TULSA, OKLAHOMA.

SAFETY HOOK.

Application filed October 1, 1924. Serial No. 741,018.

To all whom it may concern:

Be it known that I, ALBERT HOWARD NEILSON, a citizen of the United States, and a resident of Tulsa, in the county of Tulsa and State of Oklahoma, have invented certain new and useful Improvements in Safety Hooks, of which the following is a specification.

This invention relates to an improvement 10 in safety hooks, and the object of the invention is to provide a safety hook wherein the rope, cable, or other element to be engaged with the hook may be readily and easily associated therewith, and when so associated 15 serves to close or lock the hook whereby accidental displacement of the rope or cable from the hook is prevented, the safety hook being at the same time so constructed and organized that the rope or cable may be 20 readily taken from the hook when desired.

Another object is to provide a safety hook of this character and having these advantages and which is also of simple and durable construction, reliable in operation and 25 easy and comparatively inexpensive to manufacture.

Other objects and advantages of the invention reside in certain novel features of the construction, combination and arrangement 30 of parts which will be hereinafter more fully described and particularly pointed out in the appended claims, reference being had to the accompanying drawings forming part of this specification, and in which:

35 Figure 1 is a view in side elevation and illustrating one embodiment of the invention;

Figure 2 is a view thereof in longitudinal vertical section;

40 Figure 3 is a view in longitudinal vertical section, showing a slightly different form of latching mechanism; and

45 Figures 4 and 5 are detail views of the latch and locking lever employed with the construction shown in Figure 3.

Referring to the drawings wherein for the sake of illustration are shown the preferred embodiments of the invention and more particularly to Figures 1 and 2, the 50 numeral 10 designates generally the hook constituting the present invention which in-

cludes a body portion 11 hollowed out to form a chamber 12. The forward end of the chamber 12 is closed by a wall 13 integral with the body portion whereas the rear end 55 of the chamber is open, as indicated at 14. A removable plate 15 is provided on one side of the body portion 11 and provides for ready access to the interior of the chamber 12 and assembly of the parts therein as will 60 hereinafter more fully appear. The bill of the hook, designated at 16, is integrally formed with or suitably secured to the body portion 11. The face of the bill 16 with which the rope or cable is engaged inclines 65 inwardly and downwardly, as at 17, to the bight 18 of the bill so that the rope or cable after having been engaged with the face 17 will tend to move downwardly into the seat 70 constituted by the bight 18. The front wall 13 of the chamber 12 terminates at a point indicated at 19 and which overlies the inclined face 17 of the bill at a point somewhat spaced from the bight 18 so that the chamber 12 is opened to the bill of the hook 75 above the bight or seat 18 thereof.

A latch, designated generally at 20 is provided and is pivotally mounted, as at 21, on the body portion 11 of the hook. The latch 20 includes a setting finger 22 and a retaining finger 23 which define between them a recess or pocket 24 in which the rope, cable or other element engaged with the hook is adapted to be received. As clearly shown in Figure 2 the latch is so positioned on the 80 body portion of the hook that in one position thereof the setting finger 22 lies across and ahead of the seat 18, as clearly shown in dotted lines in Figure 2. When so positioned the setting finger 22 is adapted to be 85 engaged by the cable, rope or other element when the same is applied to or associated with the hook so that as the cable or rope slides down the inclined surface 17 onto the seat 18 it will be shifted from the position 90 shown in dotted lines in Figure 2 to the position shown in full lines wherein the retaining finger 23 is disposed across the entrance to the hook.

A locking lever, designated generally at 100 25 is provided and is fulcrumed, as at 26, on the body portion 11. At the end of the lever

25 opposite its fulcrum 26 it is provided with a handle portion 27 which is readily accessible from the open end 14 of the body portion. A compression coil spring 28 engages 5 the locking lever 25 at one end and the upper wall of the chamber 12 at its opposite end and tends to urge the locking lever into engagement with the latch. Preferably the ends of the spring 28 are received in recesses 25^a and 11^a provided therefor in the lock lever and the body portion respectively. The latch 20 is provided with a stop shoulder 30 and with a tooth 31 having an inclined face and a flat face, the flat face being vertical in one position. The lock lever 25 is provided with a tooth 32 which is cooperable with the stop shoulder 30 for limiting the open movement of the latch 20 and which is cooperable with the tooth 31 for 10 holding the latch 20 in closed position that is in the position shown in full lines in Figure 2. With the parts positioned as shown in dotted lines in Figure 2 the hook is set ready to receive the cable, chain, rope or other element to be associated therewith. When the rope is introduced into the hook it will engage the finger 22 and will shift the latch in a clockwise direction as viewed in Figure 2, the inclined surface of the tooth 31 camming the locking lever 25 upwardly to permit of this movement of the latch. When 15 the latch has been thrown to the full line position shown in Figure 2 the spring 28 will have caused the tooth 32 of the locking lever to snap in position behind the tooth 31 of the latch that is into engagement with the flat vertical face of the setting tooth 31. The engagement of these teeth 31 and 32 prevent the latch from swinging in a 20 counterclockwise direction, as viewed in Figure 2 and consequently precludes the possibility of the cable or rope slipping from the hook. When it is desired to release the cable or rope from the hook the handle portion 27 is grasped and the locking lever is 25 raised upwardly about its fulcrum to disengage the teeth 32 from the tooth 31 whereupon the rope or cable may be readily pulled from the hook since the latch is freely rotatable to permit of disengagement of the hook from the chain or cable.

In the form of the invention shown in Figure 3 the hook is designated at 35, and is identical in all respects with that disclosed in Figures 1 and 2, the only difference residing in the form of latching mechanism employed. This latching mechanism includes a latch member, designated generally at 36 and having a shank 37 pivotally 30 mounted, as at 38, on the body portion of the hook. At its ends opposite the pivot 38 the latch member has connected thereto a curved and hooked shaped retaining finger 39. The shank 37 is partially cut away to provide 35 a shoulder 40 for a purpose which will pres-

ently appear. A locking lever, designated generally at 41, is provided and is fulcrumed, as at 42, upon the body portion of the hook. The locking lever includes an arm 42 partially cut away to enable the arm to 70 cooperate with the shoulder 40 of the shank 37 of the latch. The lever 41 also includes a second arm 44 extending at right angles to the arm 42 and having its outer end concaved and shaped as at 45, to engage the 75 rope, cable or the like. With this arrangement the rope, cable or other element to be engaged with the hook may be associated with the hook at any time since it will coact with the inclined or camming surface 39^a of 80 the retaining finger 39 to lift the finger to permit of entrance of the rope, chain or cable. Once the cable has entered the hook the retaining finger will drop, as shown in full lines in Figure 3. When within the 85 hook the rope, chain or cable will seat against the end 45 of the arm 44 so as to hold the lever 41 in position to secure the latch against opening movement. It is to be understood that the engagement of the cable 90 with the end 44 of the arm of the lever tends to swing the arm 42 of the lever in a clockwise direction, as viewed in Figure 3 and thus tends to bring the shoulder 43 into engagement with the shank 37 of the latch to 95 hold the same against opening movement.

I claim:

1. A safety hook having a latch provided with a setting finger and a retaining finger, the setting finger being adapted to be actuated by the element engaged with the hook to throw the latch to closed position wherein its retaining finger prevents displacement of the element from the hook, said latch having a stop shoulder and a tooth provided with a flat face and a curved face, a locking lever having a tooth provided with a flat face engageable with the stop shoulder of the latch for limiting the opening movement of the latch and engageable with the flat face 100 of the tooth of the latch for holding the latch in closed position, the tooth of the lever also having a curved face cooperable with the curved face of the tooth of the latch for permitting the latch to move from open 105 to closed position, and a spring pressing the lever into engagement with the latch.

2. A safety hook having a latch provided with a setting finger and a retaining finger, the setting finger being adapted to be actuated by the element engaged with the hook to throw the latch to closed position wherein its retaining finger prevents displacement of the element from the hook, said latch having a tooth provided with a flat face and a curved face, a locking lever having a tooth provided with a flat face engageable with the flat face of the tooth of the latch for holding the latch in closed position, the tooth of the lever also having a curved face cooperable 110 115 120 125 130 135

with the curved face of the tooth of the latch for permitting the latch to move from open to closed position, and a spring pressing the lever into engagement with the latch.

5 3. A safety hook having a latch including a pivoted shank and a curved retaining finger, and a locking lever having a rope en-

gaging arm, said shank having a shoulder, said locking lever also having a shoulder engageable with the shoulder of the shank of 10 the latch to hold the latch in position to close the hook.

ALBERT HOWARD NEILSON.
